UNITED STATES PATENT OFFICE.

JOHN B. DAVIS, OF SPRINGFIELD, MASSACHUSETTS, ASSIGNOR TO GILBERT & BARKER MANUFACTURING COMPANY, OF WEST SPRINGFIELD, MASSACHUSETTS, A CORPORATION OF MASSACHUSETTS.

LIQUID-DISPENSING APPARATUS.

Application filed April 13, 1923. Serial No. 631,843.

To all whom it may concern:

Be it known that I, JOHN B. DAVIS, a citizen of the United States, residing at Springfield, in the county of Hampden and State of Massachusetts, have invented new and useful Improvements in Liquid-Dispensing Apparatus, of which the following is a specification:

This invention relates to liquid dispensing apparatus, such for example as is used for dispensing gasoline or other oils, and is more particularly concerned with improvements in the means for receiving the drip from the dispensing faucet and conducting the same back to the supply reservoir.

One example of the general type of apparatus with which this invention is concerned will be found in United States Letters Patent No. 1,305,289, granted June 3, 1919 on an invention of Charles W. Kincaid. In general, such apparatus comprises a reservoir, in which is mounted a measuring or dispensing pump to draw oil from the reservoir and deliver it through a dispensing faucet, and a movable drip receiving and conducting tube normally held by yieldable means beneath the faucet.

Outfits of this character are oftentimes supplied without charge to the retailer for use with a certain brand of oil and the filling opening of the reservoir may be locked or sealed to prevent the retailer from using the outfit with another brand of oil. However, it is possible to swing the drip tube away from the dispensing faucet, attach a hose to this tube and thereby fill the reservoir with another brand of oil in an unintended manner. This invention is concerned with the provision of means to prevent such misuse of the apparatus.

The invention has for its broad object to provide means for closing off communication between the drip tube and reservoir whenever the drip tube is moved away from, or out of drip receiving relation with, the dispensing faucet.

Other objects and advantages will appear in the following description and in the illustrative embodiment of the invention in the accompanying drawings in which—

Fig. 1 is a fragmentary elevational view, with parts in section, of a liquid dispensing apparatus embodying the invention; and

Figs. 2 and 3 are sectional plan views taken on the lines 2—2 and 3—3, respectively, of Fig. 1.

Referring to these drawings; there has been shown, by way of illustrative example, one type of liquid dispensing apparatus with which the invention is adapted to be used. The invention, however, is largely independent of the constructional features of the dispensing apparatus and many other suitable types will readily occur to those skilled in the art. That type illustrated herein is substantially like that disclosed in the above named patent.

The apparatus includes a tank or supply reservoir 5 to receive the oil and a measuring or dispensing pump mounted thereon. The pump includes a cylinder 6 which is disposed within reservoir 5 and supported by a cap plate 7 secured to the top wall of the reservoir. The piston rod of the pump is shown at 8 and is attached to a rack bar 9 which may be reciprocated vertically by means of a crank handle 10 in the usual and well known manner. The upper frame 11 of the pump is attached in upright relation to plate 7 and on this frame may be mounted one or more quantity stops 12, adapted to operate with an abutment 13 on the rack bar 9, all in the usual and known manner. The intake pipe for the pump is shown at 14 and the discharge pipe at 15, the latter extending upwardly from plate 7, being guided in frame 11, and having its upper end turned at right angles and supplied with a dispensing faucet 16 having a downwardly directed nozzle 17.

The drip tube is shown at 18 and has two laterally offset and vertically disposed portions, one of which is adapted to underlie the nozzle 17 to receive the drip. The other portion is mounted to turn in a pipe 19 which is tapped into and depends from plate 7. Pipe 19 is capped at its lower end, as shown at 20, and is provided with a longitudinal slot 21. Tube 18, at its lower end, is provided with a similar slot 22 (Fig. 3) and the slots 21 and 22 are adapted to register when tube 18 occupies the position indicated by full lines in Fig. 1. When moved out of such position, toward that indicated by dotted lines in Fig. 1, the slots 21 and 22 are moved out of registration.

- Tube 18 preferably has a conical ring 23 which rests upon a similar ring 24 on plate 7, the purpose of this arrangement being to prevent water from entering the reservoir around tube 18, where it passes through plate 5.
- 10 The nozzle 17 may likewise have a conical hood 25 to overlie the inlet end of tube 18 which end is supplied with a fitting 26, generally like that of the patent above mentioned, being cut away at 27 to slide past 15 and surround the nozzle 17.
- The tube 18 is normally held in drip receiving relation with faucet 16, as illustrated in Fig. 1 and the rear wall of fitting 26 (opposite the cut away portion 27) may 20 cooperate with nozzle 17 to arrest the tube when moved toward and into drip receiving position. Any suitable means may be employed to yieldingly hold the tube in the position just described, such as a torsion 25 spring 28, which encompasses the tube 18 and has one end 29 received in a recess provided in a circumferential flange 30 fixed on the tube. The other end 31 of spring 28 is extended tangentially (Fig. 2) 30 and strikes against one inner wall of a two part casing 33. The parts of casing 33 are drawn together by a bolt 34 and clamped to discharge pipe 15. This casing 33 encompasses spring 28 and forms a guide for tube 35 18 in its swinging movement. The upper wall of casing 33 overlies flange 30 and prevents withdrawal of tube 18 from pipe 19.
- The operation of the apparatus will readily appear from the foregoing description.
- 40 The invention has been disclosed herein, in an embodiment at present preferred, for illustrative purposes but the scope of the invention is defined by the appended claims rather than by the foregoing description.
- 45 I claim:
1. The combination with a reservoir, of means through which liquid may be withdrawn therefrom including a delivery spout, a drip conductor including an inlet

55 inlet portion opening into said reservoir, and means operable by movement of said conductor out of drip receiving relation with the spout to cut off communication between said inlet and outlet.

2. The combination with a reservoir, of means for delivering liquid therefrom including a dispensing faucet, conducting means to convey the drip from said faucet 60 back to the reservoir including an inlet portion movable into and out of drip receiving relation with the faucet and an outlet opening into said reservoir, means to yieldingly hold the inlet portion in drip receiving relation with said faucet, and valve means 65 operable by movement of said portion out of drip receiving relation with the faucet to close off communication between said portion and said outlet.

70 3. The combination with a reservoir, of means for delivering liquid therefrom including a faucet, a drip conductor mounted to move toward and away from said faucet, means for yieldingly holding the conductor 75 in position to receive the drip from said faucet, said conductor communicating with said reservoir when thus positioned, and means operable by movement of the conductor away from the faucet to cut off the 80 communication between the conductor and said reservoir.

4. The combination with a tank, of means for delivering liquid therefrom including a faucet, a drip conductor mounted to swing 85 toward and away from the faucet, means for normally holding the inlet end of said conductor beneath the faucet, means on the tank depending into the interior thereof and forming a cylindrical socket in which the outlet end of said conductor is mounted 90 for turning movement, and openings provided in said means and conductor adapted to register when the conductor is disposed in drip receiving position.

95 In testimony whereof I have affixed my signature.

JOHN B. DAVIS.
